EXHAUST SYSTEM FOR GRINDING WHEELS
AND THE LIKE

Lars Oftedal, Oslo, Norway

Application March 15, 1952, Serial No. 276,838
In Norway March 20, 1951

3 Claims. (Cl. 51—273)

1

The present invention relates to a suction-hood adapted to be employed in connection with grinding, polishing and like machines, for the purpose of carrying away the dust or the like produced during the operation of such structures.

In devices of this class it appears that the grinding wheel entrains considerable air upon its rough sides causing a fan-like effect, setting up air currents resulting in a strong outward flow of air from the hood opening, especially at the upper part thereof, where particles of grit and metal leaving the wheel, are thrown outwardly beyond the hood by said outward flow.

The main object of the invention is to utilize the fan-like effect of the wheel, creating a vacuum at both sides of the middle thereof, to counteract the said outward flow through the hood opening.

With this general object in view the invention consists in an exhaust system for a grinding wheel or the like, a hood enclosing the major portion of the wheel and having an opening in the upper forward portion thereof, a main exhaust duct communicating with the hood, outwardly directed enlargements in either side of said hood adjacent the middle of the wheel, radially extending grooves in the opposite wall portions at the upper front edge of said hood, said grooves communicating at the inner ends with the adjacent enlargement and at the outer ends with the open air.

In the drawing illustrating as an example an embodiment of the invention, Figure 1 is a rear elevation of an exhaust hood embodying the present invention; Figure 2 is a vertical cross section taken on the line II—II of Figure 1, Figure 3 is a plan view of the rear half of the hood in horizontal cross section and Figure 4 is a cross section similar to the upper portion of Figure 2 of a somewhat modified embodiment.

In the drawing 1 denotes the grinding wheel secured on a shaft 2 rotatably mounted in the bearing 3 of the grinding machine. The hood consists of two halves 4 and 5 which enclose the major portion, for example about three quarters of the circumference of the wheel, so that an opening is left in the upper forward portion of the hood as shown. At the bottom the halves form a main exhaust duct 6 for carrying away the dust, grit and metal particles created during the grinding operation. The halves 4 and 5, the division plane of which preferably coincides with the middle plane of the wheel enclose the wheel in such manner that between the sides thereof and the walls of the halves there is left only

2

narrow slits 7, except at the middle of each halves where the walls have outwardly directed cup-like enlargements 4', 5', respectively, receiving the end of the shaft 2 and the means for securing the wheel 1 thereon.

The half 5 is secured to the bearing 3 of the grinding machine by means of screws 8. At the lower side the halves 4, 5 are interconnected by means of hinges 9 and at the upper side by means of a clamping bolt 10.

At the upper front edge of the hood, where the wheel 1 runs out therefrom, each of the halves 4, 5 is provided with a vertically disposed groove or channel 11, having a cross-section which preferably increases toward the axis of the hood. Said channel or groove thus extends approximately radially and communicates at the inner end with the adjacent enlargement and at the outer end with the atmosphere.

Across the space between the halves at the upper ends of the channels 11 a tightening piece or gate 12 is arranged the sides of which project somewhat into said channels 11 and are guided therein so that the gate can be adjusted in the longitudinal direction of the channels in order to be placed in the correct position in relation to the diameter of the wheel. The lower part of the gate 12 has mainly the shape of an inverted U the legs of which lie close to the circumference of the wheel 1 and close the space between the halves 4, 5 intermediate of the channels so that said channels besides being communicating with the open air, also communicate with each other through the channel or port 13 formed by the said legs and the circumferential surface of the wheel 1.

Each of the halves 4, 5 has mounted therein a curved partition 4'', 5'' respectively which cooperate to define conduit 14. The partitions are terminally spaced from the gate 12 as shown at 15 and extend down to the main duct 6.

In the operation of the device as above described the fan-like effect of the wheel 1 during rotation thereof sets up air currents outwardly against and along the curved partition, as shown by arrows in Figure 1, said air currents being deflected by the gate 12 into the channel 14 and are exhausted through the duct 6.

This displacement of air by the rotating wheel creates in the enlargements at both sides of the wheel 1 a vacuum effecting a suction in the grooves 11 creating a downwardly flow of air therethrough which pick up the dust, grit and metal particles and carry them down through 55 the grooves or channels 11 so that these do not

continue outwardly beyond the hood. Owing to the channel or port 13 in the gate the suction in the grooves or channels 11 is equalized.

As will be understood the gate may have such a width that it extends to the bottom of each of the grooves 11 as shown at 12 in Figure 4. In this case the gate is provided with a bore 16 connecting the channel 13 with the open air. The cross sectional area of said bore may be adjusted by means of a slide valve 17 having a corresponding bore 18, or the like.

I claim:

1. In an exhaust system for a grinding wheel or the like, a hood enclosing the major portion of the wheel and having an opening in 15 the upper forward portion thereof, a main exhaust duct communicating with the hood, outwardly directed enlargements in either side of said hood adjacent the middle of the wheel, radially extending grooves in the opposite wall portions at the upper front edge of said hood, said grooves communicating at the inner ends with the adjacent enlargement and at the outer ends with the open air, a gate closing the opening in the hood intermediate of the grooves and ar- 20 25

ranged adjustably in the longitudinal direction of said grooves, and a channel in said gate connecting the grooves at both sides of the wheel.

5. In an exhaust system as in claim 1 in which the gate extends to the bottom of each of said grooves, a bore connecting the channel in said gate with the open air and means for adjusting the cross sectional area of said bore.

10. In an exhaust system as in claim 1 in which the cross sectional area of said grooves increases towards the center of the hood.
